UNITED STATES PATENT OFFICE

ANDREW A. AUGUST, OF CHICAGO, AND BENJAMIN J. VICTOR, OF OAK PARK, ILLINOIS,
ASSIGNORS TO VICTOR MANUFACTURING AND GASKET COMPANY, OF CHICAGO,
ILLINOIS, A CORPORATION OF ILLINOIS

PROTECTING DEVICE

Application filed April 9, 1930. Serial No. 442,230.

This invention relates to protecting devices for use on eyeleting and like machines and the primary object is to prevent operation of the machine until the material is properly located thus preventing injury to the material.

Another object of the invention is to provide a protecting device of simple construction and operation that may be readily attached to machines of ordinary construction without requiring alteration of such machines.

A selected embodiment of the invention is illustrated in the accompanying drawing, 15 and therein,

Fig. 1 is a perspective view of an eyeleting machine embodying a preferred form of construction of our invention;

Fig. 2 is a view partly in vertical section 20 and partly in elevation looking in at the left hand side of Fig. 1; and

Fig. 3 is a sectional view taken substantially on the line 3—3 of Fig. 2.

In the drawing, 1 indicates the standard 25 of an eyeleting machine having arms 2 and 3 extending therefrom and including a base 4. At the end of the arm 2 is a sleeve 5 having a plunger 6 mounted for vertical reciprocation therein. At the lower end of 30 the plunger 6 the top set 7 is mounted which set includes a locating pin 8 having a head 9 arranged in a recess 10 in the set 7 in which recess a spring 11 is mounted which acts on the head 9 to urge the pin 8 outwardly of the 35 end of the spindle. At the outer end of the arm 3 a socket 12 is formed having an axial opening 13 therein, into the lower end of which opening the locating screw 14 is extended. The bottom set 15 includes a stem 40 extended through a reduced portion of the opening 13 into engagement with the inner end of the locating screw 14. At the upper end of the socket 12 is a holder 16 for the bottom set 15. The sets 7 and 15 are arranged 45 in vertical alinement and when the plunger 6 is moved downwardly the eyeleting operation is carried out by these sets in the manner well understood, the material to be operated on having been previously disposed between these top and bottom sets. The

drive shaft 17 is journaled in the standard 1 and freely rotatable thereon is the drive pulley 18 retained between the collars 19 and 20 fixed to the shaft 17. In the collar 20 is a pocket 21 and an opening 22 communicates therewith. A rod 23 extends through the opening 22 into the pocket 21 and has a guide collar 24 thereon. A spring 25 is disposed around the rod 23 between the bottom of the pocket and the guide collar 24. At the outer end of the rod 23 and unitary therewith is a surface cam 26 having a notch 27 55 therein. Bearings 28 and 29 have an operating rod 30 extended therethrough on which rod a collar 31 is secured below the bearing 28. A coil spring 32 is disposed around the rod 30 between the bearing 29 and the collar 31 and normally urges the collar into engagement with the bearing 28. The pocket 21 and, therefore, the rod 23 are radially located with respect to the shaft 17 and an opening 33 in the pulley 18 is correspondingly radially located from the shaft 17. Suitable means are provided for moving the rod 30 downwardly to retract the upper end of the rod from the notch 27. The spring 25 60 acts on the collar 24 and moves the rod toward the pulley 18 and when the opening 33 moves into alinement with the rod 23 the end of the rod 23 enters the pocket 33 and interconnects the collar 20 and the pulley 18 and, therefore, the shaft 17 and the cam 26 will be rotated. As soon as the cam 26 begins to rotate the rod 30 is released and the spring 32 65 forces it upwardly into engagement with the periphery of the cam 26. When the end 34 of the cam 26 passes the rod 30 it moves upwardly until the collar 31 abuts the bearing 28. The upper end of the rod 30 will then lie in the path of the cam 26. Continued rotation brings the lowest point 35 of the cam 26 into engagement with the rod 30 and the inclination of the cam will, during continued rotation, cause said cam to be moved away from the collar 30 which will 70 retract the end of the rod 23 from the opening 33 thus disconnecting the device from the pulley 18. Immediately after retraction of the rod 23 from the opening 33 the rod 30 will drop into the notch 27 and arrest fur-

ther movement, this action being aided by braking devices commonly used in machines of this character. At the end of the drive shaft 17 opposite the pulley 18 is a link 5.37 connected to a link 38 attached by a toggle connection 39 to the upper end of the plunger 6. When the main shaft 17 is rotated the plunger 6 will be reciprocated. Our protecting device is adapted to prevent movement of the rod 30 until the material is properly located between the top and bottom sets. A collar 40 is secured at the end of the lever 41 and has an opening therein surrounded by the flange 42. The bottom set 15 is alined with the opening in the collar 40. Secured to the standard 1 is an angle bracket 43 having a hinge structure 44 thereon providing a fulcrum for the lever 41. At the end of the lever 41 opposite the collar 40 20 is a lever arm 45 the end of which is disposed below the collar 31. A spring 46 is connected to the lever 41 between the fulcrum and the lever arm 45 and acts on the lever to urge the collar 40 upwardly. The action of the 25 spring 46 is limited by a suitable stop which, in the present instance, is provided by the bearing 29 against which the end of the lever rests. The material is indicated by 47 and has an opening 48 therein in which an 30 eyelet is to be installed. The material 47 is rested on the flange 42 and pressure is applied to pivot the lever 41 downwardly. If the opening 48 is properly alined with the bottom set 15 this bottom set will enter the 35 opening 48 and permit the lever 41 to be pivoted sufficiently to retract the arm 45 from below the collar 31, as shown in dotted lines in Fig. 3. If, however, the opening 48 and the bottom set 15 are not properly alined the 40 engagement between the bottom set and the material 47 will prevent downward movement of the lever 41 and, therefore, the arm 45 will remain below the collar 31 to prevent downward movement thereof and, therefore, downward 45 movement of the rod 30. It is, therefore, apparent that proper alinement of the bottom set 15 and the opening in the material to receive an eyelet must be established before the machine can be operated. This will 50 prevent damage to the material by operation of the machine when the material is not properly alined with the sets.

While we have illustrated and described a selected embodiment of our invention, it is 55 to be understood that this is capable of modification and changes in construction without departing from the purview of the following claims.

Claims:

59 1. In a machine comprising an operating mechanism including a movable portion and a stationary portion, operating means for said movable portion, controlling means for said operating means, and means independent of said operating means for preventing

operation of said controlling means including a portion disposed below the material to be acted on by said operating mechanism.

2. In a machine comprising an operating mechanism including a movable portion and a stationary portion, operating means for said movable portion, controlling means for said operating means, and a pivotally mounted member independent of said operating means for limiting movement of said controlling means, said pivotally mounted member having a portion thereon on which material to be acted on by said operating mechanism may be rested whereby said material will engage said stationary portion and prevent movement of said pivotally mounted member from limiting position until said material is properly positioned relative to said stationary portion.

3. In a machine comprising an operating mechanism including a movable portion and a stationary portion, operating means for said movable portion, controlling means for said operating means, a pivotally mounted member independent of said operating means and having a portion at one end thereof for limiting movement of said controlling means, and a portion at the other end of said pivotally mounted member engageable by the material to be acted on by said operating mechanism.

4. In a machine comprising an operating mechanism including a movable portion and a stationary portion, operating means for said movable portion, controlling means for said operating means, a pivotally mounted member independent of said operating means and having a portion at one end thereof for limiting movement of said controlling means, yieldable means for retaining said portion in limiting position, and a portion at the other end of said pivotally mounted member engageable by the material to be acted on by said operating mechanism to move said first named portion on said pivotally mounted member from limiting position.

5. In a machine comprising an operating mechanism including a movable portion and a stationary portion, operating means for said movable portion, controlling means for said operating means, a pivotally mounted member independent of said operating means and having a portion at one end thereof for limiting movement of said controlling means, yieldable means for retaining said portion in limiting position, and a portion at the other end of said pivotally mounted member movable past said stationary portion when the material to be acted on by said operating mechanism is properly positioned relative to said stationary portion.

6. A protecting device including a pivotally mounted member having a stop portion at one end thereof, means urging said stop portion into stopping position, means

- 5 at the other end of said member adapted to be moved by material rested thereon to retract said stop portion from stopping position, and a stationary member engageable by the material to limit movement of the means engaged by said material to prevent movement of said stop portion from stopping position when said material is improperly located on said means.
- 10 7. A protecting device including a pivotally mounted member having a stop portion at one end thereof, means urging said stop portion into stopping position, and means at the other end of said member including a 15 ring member movable past a stationary member alined with the opening therein when material disposed on the ring member is positioned properly relative to said stationary member.
- 20 8. A protecting device including a pivotally mounted member having a stop portion at one end thereof, means urging said stop portion into stopping position, and means at the other end of said member including a 25 flanged collar movable past a stationary member alined with the opening in the collar when an opening in material rested on the flange of said collar is alined with the stationary member.
- 25 9. In a machine comprising an operating mechanism including a movable portion and a stationary portion, operating means for said movable portion, controlling means for said operating means, means independent of 30 said operating means for preventing operation of said controlling means and including a portion disposed below the material to be acted on by said operating mechanism, and yieldable means for retaining said portion in 40 said position.
- 35 10. In a machine which has a standard, a reciprocating member, a stationary member, a drive shaft for operating said reciprocating member, a clutch for controlling the operation of said drive shaft, and an operating member for said clutch, the combination of a lever independent of said drive shaft and pivotally mounted on said standard, said lever including a portion juxtaposed said stationary member and having a portion engageable with the operating member for said clutch, means for holding said portion in position to engage said operating member for said clutch, said last-named means being 45 yieldable whereby material rested on the portion of said lever adjacent said stationary member may move said portion when said material is properly alined with said stationary member whereby the other portion of said lever may be moved from engaging position with respect to the operating member for said clutch whereby said operating member may be moved to operate the clutch.
